SHIP'S RUDDER

Filed Sept. 20, 1927

UNITED STATES PATENT OFFICE.

JOHN TUTIN, OF SUNDERLAND, ENGLAND.

SHIP'S RUDDER.

Application filed September 20, 1927, Serial No. 220,783, and in Great Britain September 25, 1926.

This invention relates to rudders of the balanced or semi balanced type, in association with open stern frames, and the object of the invention is to effect certain improvements in such rudders.

To this end a balanced or semi balanced rudder is constructed in such a manner that that portion of the rudder which lies within the screw race has horizontal sections of complete aerofoil or streamline form, totally enclosing the corresponding portion of the main piece, said sections comprising a rudder plate, displaced laterally to one side of the main piece, to which plate is secured a suitably shaped sheathing of timber or other appropriate material. By this means certain difficulties in the construction and use of known types of stream lined balanced rudders are overcome. A rudder constructed according to the present invention is relatively light and inexpensive, easily repaired, and does not involve electric welding, whilst the sheathing, which may take various forms, including that of an aerofoil, may be readily removed at any point for inspection, repair, renewal, and the treatment of the enclosed metal surfaces to prevent corrosion. It will be understood, of course, that whilst as far as possible a smooth and regular contour of such horizontal sections is proposed, a contour which, for constructural reasons, is not perfectly smooth, will nevertheless come within the scope of the invention.

The horizontal sections, neglecting the aforesaid purely constructural departures from a smooth form, may be symmetrical about a vertical longitudinal central plane, in which case the resistance of the rudder is relatively less than for an ordinary rudder; or they may be non-symmetrical about a vertical longitudinal central plane in such a manner as to utilize the rotational velocity of the race abaft the propeller to impart a contributory propulsive thrust to the vessel as described in the specification of my application Serial No. 99537/1926. In this latter case therefore, the resistance of the rudder is relatively less than an ordinary rudder and in addition it develops an auxiliary propulsive thrust.

But in order that the invention may be more readily understood and easily carried into effect it will now be further described with the aid of the accompanying drawings in which one example is semi-diagram-

matically illustrated in side elevation by Fig. 1, Fig. 2 representing a series of sections designated A, B, C, D, E, F, G and H, to correspond to the lines similarly designated in Fig. 1. Fig. 3 shows the fore and after ends, to a larger scale, of a specific constructional detail of aerofoil form of rudder. Fig. 4 is a view of a modification to the sections shown in Fig. 2.

As shown in Figs. 1 and 2 the rudder comprises two plates 1, 2 secured to a main piece 3, the uppermost arms 4 of which serve to effect pintle connection with the head piece or arch 5 of a stern frame of the open type. The upper part of plate 1 may coincide with the central longitudinal plane of the vessel, when in normal position, as indicated in the section A. Fig. 2, but is gradually displaced, corresponding to the section B, C, D until section E is reached where the aftermost corner of the plate coincides with the aftermost corner of the lower plate 2. Such a construction differs only slightly from that of my earlier application Serial No. 99537/1926 already referred to the coincidence of the aftermost corners of the plates in line with the axis of the propeller shaft however avoiding the necessity of rope guards such as are desirable or necessary when the after edge of the rudder plates is discontinuous.

The rudder plates are in this instance slotted over the arms where these enclose the main piece, and they may also if desired be slotted over the tips of the arms forward and aft or elsewhere where it may be desirable, 19 representing the points at which such holes are formed in the rudder plates in the example illustrated. Wood members, attached to the plates secure the desired aerofoil formation. The baulks thus constituted, of which one is shown at 6 in Fig. 3 may be equipped with protector plates 7, at the nose and tail, such plates being attached by studs 8. The connection of the baulk 6 in the example illustrated is effected primarily by means of through-bolts 9, 10 being a dowel or plug employed to protect the nut 11.

Fig. 4 represents in horizontal section a stream line balanced rudder, the sheathing being attached substantially in the way illustrated in Fig. 3 and the rudder being constructed and mounted substantially in the way illustrated in Fig. 1.

A rudder constructed according to the invention may, if desired, be pivotally sup-

ported by bearings enclosing the mainpiece itself, in lieu of the pintle attachment shown in the examples.

What I claim is:—

- 5 1. A balanced rudder for screw propelled ships, comprising a main piece, plating displaced laterally to one side of the main piece and a non-metallic sheathing applied to the said plating and enclosing the main piece.
- 10 2. A balanced rudder according to claim 1 wherein the sheathing imparts to the rudder

horizontal sections which are aerofoil in shape.

- 15 3. A balanced rudder for screw propelled ships, comprising a main piece, plating displaced laterally to one side of the main piece, a non-metallic sheathing and means for removably attaching such sheathing to the plating.

Signed at Newcastle-on-Tyne this 7th day 20 of September, 1927.

JOHN TUTIN.
